BOX CAR CONSTRUCTION

George F. Zaun, San Bernardino, Calif.

Application May 23, 1931. Serial No. 539,506

3 Claims. (Cl. 105—375)

This invention relates to box car construction and particularly to a box car of the refrigerator type.

The invention has for an object the provision of a box car having certain floor ventilation features. These ventilation features are accomplished by incorporating in said box car rack members. The inventor is aware that various box cars have been constructed which embody racks, but so far as the inventor is aware, most of said racks utilize usable space within the car. The present invention has for an object the provision of racks for the floor of the car, which racks may be interfolded in such a manner as to give practically the full inside length of the car for the purpose of receiving commodities.

In one aspect, the invention has for an object the provision of a novel form of rack adapted to be incorporated in a box car or the like wherein the rack will not catch cleats on work, such as box cleats.

Another object is the provision in a box car of a plurality of rack members adapted to cooperate when in one position so as to overlie the floor of the box car, and which may be folded without any liability of the workman catching his hands during a folding operation.

Another object is the provision of a plurality of racks maintained in hinged relation, and in such a manner that wear is removed from the hinges when the racks are in extended position resting upon an object.

Another object is the provision of means adapted to cooperate with racks for holding the racks in a given position and in such a manner that space is saved and the liability of said means contacting with objects other than the racks is overcome.

The invention has for further objects the provision of means of the character stated which is simple of structure, inexpensive of manufacture, and superior to the present racks used for box cars where saving of space is considered.

With the above and other objects in view, the invention consists in the novel and useful provision, formation, construction, association, and relative arrangement of parts, members, and features, all as shown in certain embodiments in the accompanying drawings, described generally, and more particularly pointed out in the claims.

In the drawings:

Figure 1 is a vertical sectional view of a box car incorporating the invention,

Figure 2 is a transverse sectional view on the line 2—2 of Figure 1,

Figure 3 is a fragmentary plan view, partly in transverse section, of the car shown in Figure 1,

Figure 4 is a plan view of rack members incorporating the invention,

Figure 5 is a side elevation of the rack members shown in Figure 4,

Figure 6 is a view taken substantially on the line 6—6 of Figure 4, the view being partly in section,

Figure 7 is an elevation showing the racks of Figure 5 in closed position,

Figure 8 is a detail of the hinged connection existing between two of the rack units,

Figure 9 is a fragmentary detail, partly in section, of the hinged relation that exists between rack units other than those shown in Figure 8,

Figure 10 is a detail of a catch which may be utilized in practicing the invention,

Figure 11 is a sectional view on the line 11—11 of Figure 10, and,

Figure 12 is a fragmentary detail of certain elements of the invention looking in the direction of the arrows 12—12 of Figure 7.

Referring to the drawings, I have shown in Figure 1 a box car *a* commonly known as the refrigerator type, in that both ends thereof, as shown at 1 and 2, are adapted to receive refrigerating material, such as ice 3. It is customary in a refrigerator car to provide racks of some type for the floor 4 of said car, to the end that ventilation is possible in the car, and particularly when commodities are resting upon the racks. Obviously, the ice or other cooling material 3 keeps the interior of the car at a low temperature so that the commodity, if it be fruit or vegetables, does not spoil.

At the present time, it is customary to place within a refrigerator car racks which are removable from said car and these racks are often thrown out by the truckmen and are seriously damaged. Repair of the racks, and provision of new racks, is a constantly recurring expense. With my invention, I secure racks to the car in such a manner as to become an integral part of said car, and further the racks are so arranged and so grouped in their association with the car that little space is occupied by the racks. To accomplish this very desirable result, I do not group my racks along a side wall of the car but propose to place the racks adjacent the bulkheads and, in fact, abutting the

bulkheads at both ends of said car. In addition to this, I have so arranged my racks that they interfold and nest closely together, to the end that two racks occupy substantially the space that would be occupied by one rack. Further than this, when the several racks are closely nested, I secure them against movement in such a manner that no extraneous objects are presented for contact with any edibles or other perishables housed within the car. Thus, the floor of the car may be readily cleaned or the car may be utilized for other purposes and without interference from the racks.

I am aware that various systems have been employed in the past for securing the racks both to the side walls of a car and adjacent the car joists of the roof of the car, but these exigencies have not always been satisfactory.

Referring to Figure 5, I have illustrated a series of interconnected racks 7. In the present instance, four of said racks are grouped together, as shown at 5, 6, 7, and 8. In each instance, said racks include a spaced plurality of longitudinally extending rails 9 upon which are mounted slats 10. These slats have edge portions adjacent the tops thereof rounded as shown at 11. The rails 9 for the racks shown at 6 and 7 are substantially in alignment whereas the rails 9 for the racks shown at 5 and 8 are out of alignment with the said rails of the racks 6 and 7. The rails 9 for the racks at 5 and 6 are adapted to be in hinged relation and in the manner illustrated in Figure 9, wherein facing sides of the two rails are in spaced overlapped relation and with said facing sides, in the present instance, reinforced or both provided with a wear plate 12. A spacing member 13 is interposed between said plates 12 and a bolt 14 having its head counter-sunk as shown at 15 within one of the rails, is passed through aligned openings in the said rails and the spacer 13, the bolt securing said rails and spacer in the usual manner as by providing a nut 16. The plates 12 may be secured to the rails in any approved manner, such as by the means shown at 17, that is, by the employment of screw and socket members. The rack members shown at 6 and 7 which have the rails thereof in alignment are hinged together in the manner illustrated in Figures 4 and 8. In this instance, the hinges overlie the slats and are adjacent the outermost rails 9. Thus, I groove the slats adjacent ends of said rails, as illustrated at 18. The hinges employed are of the double or two-way type, in that said hinge includes a pair of strap members 19 having knuckles 20, between which knuckles and on opposite sides thereof are links 21 and 22 with pintles 23 and 24 passed through the links and said knuckles and secured in the ordinary manner. The hinge straps are secured to the rails and the slats by passing elongated bolts through the straps and openings in the rails and slats, in the manner shown in Figure 8 at 25.

It will be observed that what might be termed the adjoining ends 26 and 27 of the rails for the racks shown at 6 and 7 are curved and spaced apart from the hinge point to the base of the adjoining rails. This structure is illustrated in Figure 8. The hinged relation existing between the racks 7 and 8 is the same as that existing between the racks 5 and 6. We thus have four racks joined together at three hinge points. It is intended that the size of the rack should be sufficient to equal substantially half of the inner transverse width of the car and sub-

stantially half of the internal length of the car. Therefore, the last rack 8 would have the end slat thereof substantially on a median line of the door-way 28 of the car. The rack shown at 9 is adapted to be secured to what might be termed a sub or end rack 29. This rack 29 comprises a single slat 30 suitably mounted upon its end rails 31. The outermost rails are turnably secured to angle members 32, said angle members being fastened to the floor 4 of the car. To accomplish this, bolts 33 are passed through the rails and a leg of the angle members 32, as shown in Figure 6. The last slat 34 of the rack shown at 9 is hinged to the slat 29 through the medium of a hinge of the car illustrated in Figure 8 and, accordingly, like reference characters will apply. The slats shown at 29, 34 and 35 are transversely bored, as shown at 36, for ventilation purposes and all the slats may be bored if desired. Certain of the slats in the several rack members are provided with elongated transverse slots 37, whereby the hand may be passed through said slots for gripping the slats to move the racks.

The rack shown at 8 is provided with a transverse face plate 38 at the portion of said rack adjacent the doorway 28. The last rack 8 has secured to one of the rails, for instance, the rail shown at 39, and substantially paralleling the said rail, an elongated casing 40. This casing 100 has the lowermost end thereof closed and the upper end open, and may be secured to the rail by providing the casing with side flanges through which screws are passed for reception in said rail, as illustrated in Figure 7 at 41. Adjacent 105 the open end of the casing is placed a J-bolt 42, this bolt being secured to the rail shown at 39 and in the manner illustrated in Figure 12. Adapted for reception within the said casing and to be confined in said casing, is a link chain 43, 110 one end of which carries a ring 44. The size of the ring with relation to the J-bolt is such that the ring cannot be withdrawn from the casing, as shown in dotted lines in Figure 7.

That portion of the car adjacent a bulkhead 115 is adapted to have one of the upright members thereof recessed, as shown at 45, within which recess is received a swing catch designated generally by 46. This swing catch is conventional in form, including a member 47 which is fastened 120 to the upright and carrying a swinging member 48. This swinging member is ordinarily held against the member 47 through the medium of a slip ring 49. The swing catch is adapted to engage an eye 50 secured to the chain 43. 125

The operation, uses and advantages of the invention are as follows:

In the present instance, and considering a standard size car, I have utilized two pairs of grouped racks, each group including four rack members maintained in hinged series. The auxiliary or sub racks 29 are four in number and are placed in pairs adjacent the bulkheads. Hence, the general appearance of the racks when overlying the floor 4 of the car will be that 130 illustrated in Figures 1 to 3, inclusive. If we assume first that the racks are all overlying the floor of the car, it will be seen that the hinged relation that exists is such as to allow the racks to rest securely upon the floor without imposing any strain upon the hinges, due to the fact that I have used link type hinges for certain of the racks, to wit, the racks 6 and 7, and the same type of hinges between the sub rack and the rack shown at 9. There can be no buckling 140

between the racks, due to this hinge construction. If the racks are down, trucking may occur over the racks and the various commodities, whether perishable or not, may be stacked upon 5 the racks and adjacent the side walls of the car. The rounded edges of the racks allow for boxes to be pushed over the racks without the cleats of said boxes being engaged by the racks.

If, after the racks have been used, it is desired to fold them in order that other material 10 may be stored within the car, this may be easily done by one man. A man grasps the rack shown at 8 by passing his hand through the hand hold 15 37, whereupon he moves said rack in such a manner that a pyramiding action occurs between the racks 7 and 8. This will occur due to the hinged relation between said racks. Due to the link type of hinge that exists between the racks shown at 6 and 7, he may then drop the racks 7 and 8 which are now nested together, for the reason 20 that the rails thereof are permitted to lie adjacent each other and substantially parallel. It will be observed in this connection that the rails of the racks shown at 8 will lie adjacent the 25 slats of the racks shown at 7 and vice versa. By grasping the slat having the hand hole 37 of the rack 6, this rack may be pyramided relative to the rack shown at 9 and finally the rack shown at 9 is moved relative to the said 30 rack 29 and in such a manner that the sub rack pyramids the rack shown at 9, whereupon the racks will assume the appearance shown in Figure 7, with the slats all in substantial parallelism and closely abutting. All of the rails will be 35 substantially parallel. The loop or ring 50 is next engaged by the finger so as to pull the chain from the casing 40, whereupon the slip ring 49 is moved to allow the swing catch to operate and 40 secure the loop 50. Thus, the racks will be securely held in the position shown in Figure 7.

By placing the racks adjacent the bulkheads, I have found that space is saved within the car. These racks, by actual test, are shown to only 45 extend substantially ten inches from the bulkhead when the racks are closely nested together in the manner shown in Figure 7. Where double rack systems are utilized that are adapted to extend along the side of the car, it will immediately be seen that for a car some 33 feet 50 in length, that the racks would occupy considerable space, as each group of racks would extend out approximately five inches from the side wall. In considering the height of the car, it will immediately be seen that this entails 55 considerable loss of space that might otherwise be utilized. In other words, it is equivalent to reducing the transverse width of the car some ten inches. Furthermore, the present construction permits boxes and barrels to align together because there is no obstruction on the side

walls, as would be the case where the boxes and barrels are piled one upon the other. If side racks are utilized, the barrels and boxes could not be aligned throughout the full height of the car.

When folding the racks, the construction of the hinges permits the racks to interfold in such a manner that the hands cannot be injured, as is self-evident upon inspection of the drawings.

The provision of the pocket or casing for receiving the chain permits the chain to be out of the way when not in use and is superior to that type of fastening wherein a chain hangs loosely against a wall. Such chains often cause damage to fruit and other perishables by swinging due to motion of the car.

When it is desired to use the racks again, the swing catch releases the chain and the racks may be brought to a floor level by reversing the action heretofore described for nesting the racks together.

It is obvious that various changes and modifications and variations may be made in practicing the invention and adapting it to various uses and purposes other than for the one described, without however departing from the true spirit of the invention.

I claim:

1. Improvements in racks for box cars and the like, comprising a pair of racks maintained in alignment, hinge means for securing the racks in working relation, one of said racks being provided with a housing, a link chain within said housing adapted to be extended therefrom, and a swing catch secured to the box car for engagement with said chain for securing the racks in substantial parallelism.

2. In railway box car construction having a bulkhead, a plurality of hinged related rack members, said rack members being adapted to 105 be relatively moved to bring said racks in substantial parallelism, and a normally housed chain secured to one of said racks and a swing catch secured to the bulkhead for engagement with the chain when the racks are in substantial parallelism.

3. The combination in a box car having a bulkhead, of two groups of racks within said car, both groups comprising four hinged related racks, hinge means for securing a rack of both groups within said car adjacent said bulkhead, the racks of both groups being adapted for movement to nest the same in substantial parallelism adjacent said bulkhead, a housing for one of said racks, a link chain within said 125 housing and adapted to be extended therefrom, and a swing catch secured to the bulkhead for engagement with said chain to in turn secure the racks when in substantial parallelism.
